UNITED STATES PATENT OFFICE.

HERMAN C. PRIEBE, OF BLUE ISLAND, ILLINOIS.

RAILROAD CAR.

Application filed December 19, 1923. Serial No. 681,609.

To all whom it may concern:

Be it known that I, HERMAN C. PRIEBE, a citizen of the United States, residing at Blue Island, in the county of Cook and State of Illinois, have invented a certain new and useful Improvement in Railroad Cars, of which the following is a full, clear, concise, and exact description.

My invention relates to railroad cars and has for its general object the provision of improved side bearings.

In accordance with my invention, side bearings are interposed between the truck and body bolster of a car, each side bearing being adjustable into functioning position by one of the bolsters between which it is interposed when these bolsters are turned upon their common axis out of the upright plane which they occupy when upon a straight track.

In the preferred embodiment of the invention, the side bearings are mounted upon the truck bolster and are normally clear of the body bolster but so related thereto as to be adjustable thereby into functioning position. These side bearings are desirably in the form of oscillating rollers which are self restoring to nonfunctioning position and which are provided with lugs engageable by the body bolster in order that they may be brought into functioning position. Two such rollers are mounted in symmetrical relation upon each end of the truck bolster, a portion upon the body bolster being disposed between the lugs so that one roller, at each end of the truck bolster, or the other, is alone brought into functioning position, according to the direction in which the truck and body bolsters are relatively turned. The rollers are desirably made self restoring by being counterweighted in a manner to cause the rollers to return to normal as the body bolster moves away from the lugs thereof.

The invention will be more fully explained by reference to the accompanying drawings in which Fig. 1 is a cross sectional view of a portion of a car body with the bolsters and a truck beneath the same, portions of the truck being shown in section; Fig. 2 is a sectional view on line 2—2 of Fig. 1; Fig. 3 is a cross sectional view on line 3—3 of Fig. 1; Fig. 4 is a view, similar to Fig. 3, but with the rollers and the bolsters in changed position; Figs. 5 and 6 are sectional views respectively taken on lines 5—5, 6—6 of Fig.

4; Fig. 7 is a perspective view showing a modification of a part of the structure; and Fig. 8 is a fragmentary sectional view illustrating another modification.

Like parts are indicated by similar characters of reference throughout the different figures.

The portion 1 of a car body of one construction is illustrated, though it is understood that the invention is not to be limited to any particular form of car. Such car body is provided with two body bolsters, one near each end thereof, of which the drawings illustrate but one body bolster 2. Each body bolster is assembled by means of a center bearing 3 with the bolster 4 of a wheel truck. In the structure exhibited in all except Figs. 7 and 8, the truck bolster is formed in a casting having upwardly projecting pairs of ears 4', 4"—5, 5 which are arranged upon chords of a circle whose center is in the axis of the center bearing. A roller 6 is interposed between each pair of the ears 4' and another roller 7 is interposed between the ears 5 of each remaining pair. Each roller bears at its bottom either upon the liner 8 upon the top wall of the truck bolster, as illustrated, most thoroughly, in Fig. 3, or directly upon the top wall of the truck bolster as illustrated in Fig. 8. The rollers are formed with arcuate surfaces 9 where they engage the truck bolster and with arcuate surfaces 10 concentric with the arcuate surfaces 9 that are to be brought into engagement with the body bolster when the two bolsters are relatively turned upon the axis defined by the center bearing. Each roller is sufficiently flattened as indicated at 11 to be brought, at this portion thereof, so far within the circle of the curved surfaces 9 and 10 as to normally afford a gap 12 between such roller and the body bolster, a position which is to obtain when the two bolsters are in the same upright plane or parallel. The rollers are formed with extensions 12', these extensions in each pair of rollers interleaving, these extensions sufficiently counter-weighting the rollers so that their upper portions will turn toward each other in their self restoring adjustment to their normal positions. The top wall of the truck bolster is formed with an opening 13 at each end thereof into which the counter-weighting extensions 12' project. Each extension is formed with a bulge 14 that en-

gages one side of the opening 13 to limit the extent to which the rollers may move in their self restoring adjustment. Each roller is formed with a lug 15 and each body bolster 5 has a downwardly continuing portion 16 at each end which is interposed between the lugs 15 of the underlying pair of symmetrically arranged rollers. When the bolsters are in angular relation by being relatively 10 turned out of their normal upright plane, one or the other of the lugs 15 at each side of the car is engaged by the adjacent bolster portion 16, according to the direction of the relative turning movement of the bolsters, 15 whereby the rollers having such engaged lugs are turned to bring their arcuate portions 10 into engagement with the bottom of the body bolster portions 16 whereby the body bolster is then also supported upon the 20 ends of the truck bolster to prevent the car body from sagging when the car is rounding curves. The rollers are desirably formed with arcuate openings 17 therethrough which receive pins 18 that are carried by the 25 ears 4', 4'-5, 5. These pins serve to assure the maintenance of the assembly of the rollers with the truck bolster.

Having thus described my invention I claim as new and desire to secure by Letters 30 Patent the following:—

1. The combination with a car truck bolster; of a car body bolster; and oscillating rollers interposed between the bolsters and each formed to support the body bolster, 35 when turned to one position and to be free of this supporting relation when turned to an alternative position and each having a lug engageable with a bolster to be turned thereby to functioning position when the bolsters are angular and each being self-restoring to non-functioning position when the bolsters are parallel.

2. The combination with a car truck bolster; of a car body bolster; and oscillating 45 rollers interposed between the bolsters and each having a rounded portion supporting the body bolster, when turned to one position and a flattened portion to be free of this supporting relation when turned to an 50 alternating position and each having a lug engageable with a bolster to be turned thereby to place its rounded portion uppermost when the bolsters are angular and each being self-restoring to place its flattened portion uppermost when the bolsters are parallel.

3. The combination with a car truck bolster; of a car body bolster; and oscillating 60 rollers interposed between the bolsters and each formed to support the body bolster, when turned to one position and to be free of this supporting relation when turned to an alternative position and each having a lug engageable with a bolster to be turned 65 thereby to functioning position when the bolsters are angular and each being self-restoring to non-functioning position when the bolsters are parallel.

bolsters are angular and each being weighted to be self-restoring to non-functioning position when the bolsters are parallel.

4. The combination with a car truck bolster; of a car body bolster; and oscillating 70 rollers interposed between the bolsters and each having a rounded portion supporting the body bolster, when turned to one position and a flattened portion to be free of this supporting relation when turned to an 75 alternating position and each having engagement with a bolster to be turned thereby to place its rounded portion uppermost when the bolsters are angular and each being weighted to place its flattened portion 80 uppermost when the bolsters are parallel.

5. The combination with a car truck bolster; of a car body bolster; and oscillating 85 rollers interposed between the bolsters and each having a rounded portion supporting the body bolster, when turned to one position and a flattened portion to be free of this supporting relation when turned to an alternating position and each having a lug 90 engageable with a bolster to be turned thereby to place its rounded portion uppermost when the bolsters are angular and each being weighted to place its flattened portion 95 uppermost when the bolsters are parallel.

6. The combination with a car truck bolster; of a car body bolster; and oscillating 100 rollers interposed between the bolsters and each having a rounded portion supporting the body bolster, when turned to one position and a flattened portion to be free of this supporting relation when turned to an alternating position and each having engagement with the body bolster to be turned 105 thereby to place its rounded portion uppermost when the bolsters are angular and each being self-restoring to place its flattened portion uppermost when the bolsters are parallel.

7. The combination with a car truck bolster; of a car body bolster; and oscillating 110 rollers interposed between the bolsters and each formed to support the body bolster, when turned to one position and to be free of this supporting relation when turned to an 115 alternative position and each having a lug engageable with the body bolster to be turned thereby to functioning position when the bolsters are angular and each being self-restoring to non-functioning position when 120 the bolsters are parallel.

8. The combination with a car truck bolster; of a car body bolster; and oscillating 125 rollers interposed between the bolsters and each having a rounded portion supporting the body bolster, when turned to one position and a flattened portion to be free of this supporting relation when turned to an alternating position and each having a 130 lug engageable with the body bolster to be

turned thereby to place its rounded portion uppermost when the bolsters are angular and each being self-restoring to place its flattened portion uppermost when the bolsters are parallel.

9. The combination with a car truck bolster; of a car body bolster; and oscillating rollers interposed between the bolsters and each formed to support the body bolster, when turned to one position and to be free of this supporting relation when turned to an alternative position and each having a lug engageable with the body bolster to be turned thereby to functioning position when the bolsters are angular and each being weighted to be self-restoring to non-functioning position when the bolsters are parallel.

10. The combination with a car truck bolster; of a car body bolster; and oscillating rollers interposed between the bolsters and each having a rounded portion supporting the body bolster, when turned to one position and a flattened portion to be free of this supporting relation when turned to

an alternating position and each having engagement with the body bolster to be turned thereby to place its rounded portion uppermost when the bolsters are angular and each being weighted to place its flattened portion uppermost when the bolsters are parallel.

11. The combination with a car truck bolster; of a car body bolster; and oscillating rollers interposed between the bolsters and each having a rounded portion supporting the body bolster, when turned to one position and a flattened portion to be free of this supporting relation when turned to an alternating position and each having a lug engageable with the body bolster to be turned thereby to place its rounded portion uppermost when the bolsters are angular and each being weighted to place its flattened portion uppermost when the bolsters are parallel.

In witness whereof, I hereunto subscribe my name this 8th day of December A. D., 1923.

HERMAN C. PRIEBE.
